UNITED STATES PATENT OFFICE.

JOHN K. SHAW, OF MINNEAPOLIS, MINNESOTA, ASSIGNOR TO B. G. DAHLBERG, OF ST. PAUL, MINNESOTA.

ORNAMENTAL PANEL OR COVERING.

1,312,056.

Specification of Letters Patent.

Patented Aug. 5, 1919.

Application filed May 23, 1918. Serial No. 236,165.

To all whom it may concern:

Be it known that I, JOHN K. SHAW, a citizen of the United States, residing at Minneapolis, in the county of Hennepin and State 5 of Minnesota, have invented certain new and useful Improvements in Ornamental Panels or Coverings; and I do hereby declare the following to be a full, clear, and exact description of the invention, such as 10 will enable others skilled in the art to which it appertains to make and use the same.

This invention relates to ornamental panels or wall coverings of fibrous material, and has for its object to strengthen and 15 beautify said panels in a manner more efficient and less expensive than those heretofore proposed.

With these and other objects in view the invention consists in the novel details of 20 construction and combinations of parts more fully hereinafter disclosed and particularly pointed out in the claims.

Referring to the accompanying drawings forming a part of this specification in which 25 like numerals designate like parts in all views;

Figure 1 is a diagrammatic plan view of a finished panel showing one form of fastening strip;

30 Fig. 2 is an enlarged sectional detail view of the panel material taken on the line 2**2 of Fig. 1;

Fig. 3 is a view similar to Fig. 1 but disclosing a different form of fastening strip;

35 Fig. 4 is a sectional view of a further modified form of fastening strip;

Fig. 5 is a view similar to Fig. 4 of the modified form of fastening strip shown in Fig. 3;

40 Fig. 6 is a sectional view similar to Fig. 2 but showing another form of fastening strip; and

Figs. 7 and 8 are each sectional views showing still further modified forms of 45 fastening strips.

1 indicates sheets, slabs, blocks or other shapes of the fibrous paper board material known on the market as "insulite," 2 the joints that exist between the individual blocks when they are laid on a support 2', Fig. 6, to form a panel or wall covering, and

30 and 40, 50, 60, 70 and 80 different forms of fasteners that may be used in securing the end portions 6 of said blocks together as well as in protecting and hiding their joints 55 or seams 2.

In order that the invention may be the more clearly understood, it is said the paper board material known as "insulite" differs radically from the ordinary paper boards of 60 commerce in that it is very porous, and therefore it has unusually high heat insulating and sound deadening properties. Its specific gravity is often not higher than, say, two tenths or three tenths and therefore it 65 resembles cork in many of its physical properties. But these most desirable properties give rise to a structure whose edges are very fragile or brittle and easily so injured as to present a ragged appearance. This is owing to the unusually large and long fibers that are employed in making the board, and to the rather imperfect natural bonding of 70 these fibers at the extreme edges so that the latter tear or break if subjected to rough 75 usage. In other words one class of fibers going to make up these boards may be, say 1/8 of an inch wide and 1/2 inch long so that they are sliver like; another set of fibers are thread like in that they may have a diameter 80 of from 1/32 to 1/64 of an inch and may be from 1/2 inch to 1 inch long or longer; a third set are hair like in that they may have a diameter of say from 1/100 to 1/200 of an inch and a length of say from 1/2 inch 85 to 1 inch or longer; while a fourth set of fibers are or may be identical with the fibers used in making paper.

In dealing with a structure such as that just disclosed, it is found in practice that 90 its surface such as 7 and 8 may be highly ornamented as by coloring or by covering with plastic materials, but the extreme edges of the individual blocks do not present such sharp, clean surfaces as to make it an easy 95 job to fit them together in a way sufficiently close to present a pleasing appearance.

According to this invention, I avoid the above difficulty and at the same time protect and strengthen the end edges 6 by proceeding as follows: I make no effort at fitting the individual blocks closely together,

but merely let the joints or seams make such an appearance as a rapid handling of the material will produce, being careful, however, to see that such joints are not wider than will be safely spanned by the heads such as 10, 11 and 12 of the fastening strips 3, 4 and 5 respectively.

After said blocks 1 are thus brought together, a fastening strip such as 3, having a shank 13 and provided with the barbs 14, is thrust down into the seam or joint 2, and its head forced down into contact with the comparatively porous, soft, or compressible material of the blocks 1.

15 I prefer to provide an edge member such as 15 which may be readily forced into the body of the material 1, and thereby more firmly unite said blocks.

Should the head 10 be concave as shown in Fig. 7, it may be filled with a plastic or other material to match the coloring or surfacing of the blocks 1, or it may be itself of such a color and finish as to need no filling. If the blocks 1 are surfaced to imitate stone, the crack 16, Fig. 5, can be conveniently filled with a plastic to appear as a bonding material, but in such cases the head 12 will be preferably flattened out against the surfaces of said blocks or tiles 1.

30 In the somewhat modified form of fastening strips shown in Fig. 4, the single piece of sheet material instead of being folded on itself to form the prong member as in Fig. 2 is bent upon itself to form the head, and the latter is convex as shown.

35 In the still further modified form of fastening strip shown in Fig. 5, the prong construction is similar to that shown in Fig. 2, but the head is made of a single thickness, 40 while the prong is formed by doubling the metal upon itself, and instead its extreme edges 17 are somewhat sharp, so that they may be forced into the body of the material 1.

45 In the modified form of construction shown in Fig. 6, the head 20 is rounded as shown, it enters a correspondingly rounded cavity 21 in the material, and between the ends of its prongs 23 I insert a wedge 24 or 50 other spreader, in order to make the barbs 25 bite into the material and also to lock them in place. Somewhat the same locking effect is produced when plaster 25 is inserted into the crack or opening 16 in Fig. 5.

55 The modified form of fastener 70 shown in Fig. 7 is provided with a prong 27 of a single thickness of metal and with spreading wings 28 formed by folding the metal 60 upon itself as shown, thus producing the space 29 which may be ornamented as described.

65 In the still further modified form of fastener 80 shown in Fig. 8, the head 80 is of a triangular cross section and the shank

31 is of the same general construction shown in Fig. 2.

From the foregoing it will now be clear that I may employ a large variety of fastening strips for hiding irregular joints 2, 70 while at the same time enhancing the appearance of the panels and strengthening the whole surface in general. In all the forms, however, the strips are made of very thin metal, in order that they may be readily 75 wedged into the seam or joints 2, between the blocks 1, and a plurality of thin yielding spring prongs projecting toward the head portions are provided, which enter the insulite edges and aid in holding the head 80 portions in place.

The fastening strips are cut into different lengths such as 19 and 20, see Fig. 1, or they may be of uniform lengths, and beveled at the ends as illustrated at 21, Fig. 3. 85

What I claim is:—

1. In an ornamental covering, the combination of a plurality of body portions composed of porous paper board material known as insulite, having fragile edges disposed with adjoining meeting edges; and a fastening strip provided with prongs engaging said fragile edges occupying the space between said meeting edges, and with a head contacting with and overlying and concealing the material adjacent said meeting edges, substantially as described. 95

2. In an ornamental covering, the combination of a plurality of porous body portions composed of paper board material 100 known as insulite, having fragile edges disposed with adjoining meeting edges; and a fastening strip provided with an extension having barbs entering said fragile edges and occupying the space between said meeting 105 edges, and with a head contacting with, overlying, entering and concealing the fragile material adjacent said meeting edges, substantially as described.

3. In an ornamental panel the combination of a plurality of porous, fragile insulite body portions disposed with their fragile edges in close proximity to each other forming seams; fastening strips provided with prongs occupying said seams, engaging 110 the fragile edges thereof, and disposed at right angles to each other, said strips also provided with strip like heads adapted to be pressed against, to extend over, protect and conceal the fragile material adjacent 120 said seams, substantially as described.

4. The herein described fastening strip provided with a prong composed of two flat folded body portions, having free ends and a space between them; and an oblong curved 125 head portion consisting of integral extensions of said body portions disposed on each side of said space, substantially as described.

5. In an ornamental panel the combination of a plurality of porous insulite body 130

portions having fragile edges in close proximity to each other forming seams; and fastening strips of thin metal provided with enlarged strip like head portions adapted to be 5 pressed against, to extend over, protect, and conceal said fragile edges and seams, and also provided with thin metal, readily yield-

ing, spring prongs occupying said seams, projecting toward said heads, and engaging the fragile edges of said insulite material 10 to aid in holding said head portions in place, substantially as described.

In testimony whereof I affix my signature.
JOHN K. SHAW.
